UNITED STATES PATENT OFFICE

OLIVER B. McCLINTOCK, OF MINNEAPOLIS, MINNESOTA, ASSIGNOR TO O. B. McCLINTOCK CO., OF MINNEAPOLIS, MINNESOTA, A CORPORATION OF MINNESOTA

DESIGN FOR A REVOLVING HOLD-UP DETERRENT

Application filed December 22, 1930. Serial No. 38,067. Term of patent 7 years.

To all whom it may concern:

Be it known that I, OLIVER B. McCLINTOCK, a citizen of the United States, residing at Minneapolis, in the county of Hennepin and State of Minnesota, have invented a new, original, and ornamental Design for a Revolving Hold-Up Deterrent, of which the following is a specification, reference being had to the accompanying drawing, forming part thereof.

The figure is a perspective view of the revolving hold-up deterrent, showing my new design, the opposite side of which is identical with that shown in the drawing.

I claim:

The ornamental design for a revolving hold-up deterrent, as shown and described.

OLIVER B. McCLINTOCK.
